(57) **CLAIM**

The ornamental design for a boat docking assist apparatus, as shown and described.

DESCRIPTION

FIG. 1 is a top view of my new design for a boat docking assist apparatus.

FIG. 2 is a front view of my new design for a boat docking assist apparatus.

FIG. 3 is a left end view of my new design for a boat docking assist apparatus.

FIG. 4 is a right end of my new design for a boat docking assist apparatus.

FIG. 5 is a front perspective view of my new design for a boat docking assist apparatus; and,

FIG. 6 is a back perspective view of my new design for a boat docking assist apparatus.

1 Claim, 4 Drawing SheetsFIG. 1

FIG. 2

FIG. 3

FIG. 4

FIG. 5

FIG. 6
